UNITED STATES PATENT OFFICE

154,606

DESIGN FOR A FISH LURE

George H. Habel, Detroit, Mich.

Application January 3, 1948, Serial No. 143,534

Term of patent 3½ years

(Cl. D31—4)

To all whom it may concern:

Be it known that I, George H. Habel, a citizen of the United States of America, residing at Detroit, in the county of Wayne and State of Michigan, have invented a new, original, and ornamental Design for Fish Lure, of which the following is a specification, reference being had to the accompanying drawing, forming a part thereof, wherein:

Figure 1 is a perspective view of a fish lure, showing my new design;

Fig. 2 is a top plan view of the same;

Fig. 3 is a side elevational view of the same;

Fig. 4 is a bottom plan view of the same;

Fig. 5 is a rear end elevational view of the same; and

Fig. 6 is a front end elevational view of the same.

The essential features of my design reside in the portion shown in full lines.

I claim:

The ornamental design for a fish lure, substantially as shown and described.

GEORGE H. HABEL.
